ADJUSTABLE CENTER REFLEX TABLE

Phillip R. Koerper, Culver City, Calif.

Application November 29, 1948, Serial No. 62,523

5 Claims. (Cl. 128—70)

1

This invention relates to folding or collapsible tables of the type commonly referred to as operating tables and particularly adapted for use in osteopathic, chiropractic, and electrotherapeutic treatments, and in particular the invention relates to a table of this type having a center yielding or reflex section and in which the parts are adapted to be folded to form a suitcase.

The purpose of this invention is to provide a table adapted for chiropractic and other treatments that may be used in the office and that may readily be folded so that it may also be used for residence calls.

In the usual tables of this type the parts are relatively heavy and cumbersome so that they are not adapted to be readily folded and carried in an automobile, car, or train and, therefore, they are not adapted for residence use. With this thought in mind this invention contemplates a table adapted to be folded to form a suitcase in which the operative surfaces are padded to form cushions and in which the frame work and folding legs are formed of comparatively few parts and of lightweight material.

The object of this invention is, therefore, to provide means for constructing a collapsible or folding table wherein the folding elements are comparatively small, of lightweight material, and adapted to be folded into a comparatively small area.

Another object of the invention is to provide an improved table for chiropractic treatments and the like which is formed with a yielding center section and in which all of the parts may be folded into a compact case representing a suitcase.

Another object of the invention is to provide a folding portable table of comparatively light weight construction in which the table when set up has sufficient rigidity to permit chiropractic and osteopathic treatments.

A further object of this invention is to provide an improved portable folding table adapted for chiropractic treatments and the like which is of a simple and economical construction.

With these and other objects of the invention in view, the invention consists of the new and useful combination, construction, and arrangements of parts hereinafter more fully described, set forth in the claims appended hereto and disclosed in the accompanying drawings forming parts hereof, wherein:

Figure 1 is a view showing a side elevation of the table in the set up position;

2

Figure 2 is a vertical longitudinal section through the table in the position shown in Figure 1 with the center section shown in the depressed position in dotted line;

5 Figure 3 is a plan view of the table in the position as illustrated in Figure 1;

Figure 4 is a view looking upward toward the under side of the table with the parts in the position as shown in Figure 1;

10 Figure 5 is an elevational view looking toward the under side of the section of the table that is formed in two parts with the legs in the folding position therein;

Figure 6 is a similar view looking toward the complete section of the case and showing the legs folded therein;

15 Figure 7 is a plan view showing the table in the folded position;

Figure 8 is a sectional plan through the table showing the parts in the folded position;

20 Figure 9 is a typical cross section through the table showing the parts in the set up position and illustrating the legs in the end section of the table;

25 Figure 10 is a similar section taken on line 10—10 of Figure 2 showing the resilient legs for supporting one side of the center section of the table;

30 Figure 11 is a detail showing a vertical section through one of the resilient legs used on the center section of the table.

35 Referring now to the drawings wherein like reference characters denote corresponding parts the portable folding table of this invention includes a complete section 10 which when folded forms one side of the case, hinged end sections 11 and 12 which when folded form the other side of the case, and a head rest 13.

40 The section 10 is formed with a box-like frame having a side wall 14 with ends 15 and 16 and sides 17 and 18. The wall 14 is covered by a comparatively soft cushioning material such as sea foam or sponge rubber and this is covered with a finishing layer of material such as leatherette. The cushioning material, in all sections, is indicated by the numeral 19 and the leatherette by the numeral 20 and it will be noted that the leatherette extends downwardly across the sides and ends with the edge thereof folded around the sides and ends of the case.

45 This material may be gummed to the walls of the case or secured thereto by any suitable means. The sections 11 and 12 are also of box-like formation, the outer hinged section 11 having 50 a side panel 21 with an end 22 and side walls

55 a

23, and the inner hinged section 12 having a side panel 24 with an end 25 and sides 26 and 27. The sections 11 and 12 are hinged together by a piano like hinge 28 and the sides are retained in the open position by jackknife braces 29.

The section 10 is supported on four legs 30 and the legs are pivotally attached to clip angles 31 on the side wall by pins 32. The legs are supported in upright positions by jackknife braces 33 which are pivotally attached to the legs by 10 a pin 34 and to the side wall 14 by clips 35 and pins 36. The pairs of legs at the ends are supported by tie rods 37 as shown in Figures 2 and 9. With the parts arranged in this manner the legs may readily be folded into the open area in 15 side of the section 10 as shown in Figure 6.

The section 11 is supported by similar legs 38 which are pivotally mounted on the side wall 21 by clip angles 39 and pins 40. These legs are supported in the upright position by jackknife braces 41 that are pivotally attached to the legs by pins 42 and to the side wall 21 by clips 43 and pins 44. The section 11 is also provided with legs 45 that are pivotally attached to the side wall 21 by clip angles 46 and pins 47 and these legs are supported from the legs 38 by braces 48 which are attached to the legs 38 at one end by bolts 49 and to the legs 45 at the other by bolts 50.

The section 12 is suspended from the section 11 at one end by the hinge 28 and the opposite end is supported by legs 51 which are formed as shown in Figure 11 with inner telescoping sleeves 52 and with the sleeves held in extended positions by springs 53 the lower ends of which rest on pins 54 in the outer tubes 51 and the upper ends of which engage pins 55 in the inner tubes 52.

The upper ends of the tubes 52 of the legs 51 are pivotally mounted on the panel 24 of the section 12 by clips 56 and pins 51, and these legs are adapted to fold into the interior of the sections 11 and 12, as shown in Figures 5 and 8. The lower ends of the legs 51 are attached by a cross brace 58 as shown in Figure 10. The adjoining edges of the sides of the sections 11 and 12 are beveled as shown at the points 59 and 60 and with the sections connected by the hinge 28 and the outer end of the section 12 supported on the legs 51 this section may be pressed downward as indicated by the dotted lines in Figure 2, which provides a center yielding or reflex section to facilitate chiropractic treatments.

The head rest 13 is formed with two outwardly extending arms 61 and 62 and these are provided with a clip angle 63 that may be removably mounted thereon by screws 64 through which the head rest may be removably attached to the end of the section 11 by thumb screws 65. The head rest may be readily removed and packed inside of the case.

The legs are provided with cup shaped elements of rubber or other resilient material as indicated by the numeral 66 which hold the table rigid in the operative position as shown in Figure 1.

The lower edges of the sections of the table are provided with separable fasteners 67 through which the sections may be hinged together and the upper edges are provided with snap fasteners with sections 68 thereof on the sections 11 and 12 and coacting sections 69 on the section 10. The section 10 may also be provided with a handle 70.

With the parts arranged in this manner the legs may be folded into the open areas in the sections as shown in Figures 5, 6 and 8 and with the sec-

tions fastened together as shown in Figure 7 the device will have the appearance of a suitcase or bag and may readily be carried in a motor vehicle, street car, plane, or train. When it is desired to use the table it is only necessary to open the sections and draw the legs outward to the positions shown in Figure 2. With the table set up in this manner it may readily be used for osteopathic, chiropractic, and electrotherapeutic treatments, and particularly for treatments of the spine, the patient may be placed face down on the table and the lower parts of the spine manipulated at the will of the operator. The center reflex section of the table is adapted to move downward about 4 inches under pressure exerted by the operator on the portion of the patient's body positioned above this section. The table provides sufficient room for the operator to adjust the patient to the dorsal and lumbar region efficiently and the yielding center section does not interfere with the comfort of the patient in other treatments such as adjusting a sacroiliac.

It will be understood that modifications may be made in the design and arrangement of the parts without departing from the spirit of the invention.

What is claimed is:

1. A portable folding table comprising two substantially hollow complementary box-like sections, one of said sections being rigid and the other hinged midway of the length thereof, legs pivotally mounted in the rigid section and constructed to fold into the open area therein, legs pivotally mounted in one of said hinged sections and constructed to fold into open areas in said sections, diagonally disposed jack knife braces for holding the legs in the sections in upright positions, the other of said hinged sections supported at one side by the said hinged section having the legs thereon through the hinge, legs having resilient elements therein supporting the side of said other hinged section opposite to that on which the hinge is positioned and pivotally mounted in said section, and separable fasteners removably securing the sections together.

2. A portable folding table comprising two substantially hollow complementary box-like sections, one of said sections being rigid and the other hinged midway of the length thereof, legs pivotally mounted in the rigid section and constructed to fold into the open area therein, legs pivotally mounted in one of said hinged sections and constructed to fold into open areas in said sections, diagonally disposed jack knife braces for holding the legs in the sections in upright positions, the other of said hinged sections supported through the hinge at one side by said hinged section having the legs thereon, legs having resilient elements therein supporting the side of said other hinged section opposite to that on which the hinge is positioned and pivotally mounted in said section, and separable fasteners removably securing the sections together, the outer surfaces of said box like sections covered with flexible material with cushioning means under the said flexible material.

3. A portable folding table comprising two substantially hollow complementary box-like sections, one of said sections being rigid and the other hinged midway of the length thereof, legs pivotally mounted in the rigid section and constructed to fold into the open area therein, legs pivotally mounted in one of said hinged sections and constructed to fold into open areas in said

sections, diagonally disposed jack knife braces for holding the legs in the sections in upright positions, the other of said hinged section supported at one side by the said hinged section having the legs thereon through the hinge, legs having resilient elements therein supporting the side of said other hinged section opposite to that on which the hinge is positioned and pivotally mounted in said section, cup shaped resilient elements positioned on the lower ends of the legs, and separable fasteners removably securing the sections together.

4. A portable folding table comprising two substantially hollow complementary box-like sections, one of said sections being rigid and the other hinged midway of the length thereof providing outer and inner hinged sections, legs pivotally mounted in the rigid section and constructed to fold into the open area therein, legs pivotally mounted in the outer hinged section and constructed to fold into an open area in said section, diagonally disposed jack knife braces for holding the legs in the sections in upright positions, the said inner hinged section being supported at one side by the outer hinged section having the legs thereon, legs having resilient elements therein supporting the side of said hinged section opposite to that supported by the outer hinged section and pivotally mounted in said section, a head rest removably mounted on the end of the outer section, and separable fasteners removably securing the sections together.

5. A portable folding table comprising two substantially hollow complementary rectangular

shaped cases having side walls with ends and sides, suitable covering material covering the outer surfaces of said cases, a layer of cushioning material under said covering material, one of said cases being rigid and the other hinged midway of the length thereof, legs pivotally mounted by clip angles to the side wall of the rigid case and constructed to fold within said case, legs pivotally mounted in one of said hinged sections of the other case and adapted to fold within said case, said legs also mounted by clip angles through the side wall of the case, diagonally positioned jack knife braces supporting the legs in upright positions, the other of the hinged sections of the case supported at one side by the section having the legs therein by the hinge, telescoping legs supporting the other side of said hinge section, resilient means in said telescoping legs for urging the said legs to extended positions, friction cups on the ends of the legs of both of the cases, means removably attaching both of the cases together, and a handle mounted on a side of one of the cases.
